UNITED STATES PATENT OFFICE.

HAMILTON BALUSS, OF KENNETT SQUARE, PENNSYLVANIA.

ELECTRIC REGULATOR.

1,270,917.

Specification of Letters Patent.

Patented July 2, 1918.

Application filed November 22, 1915. Serial No. 62,841.

To all whom it may concern:

Be it known that I, HAMILTON BALUSS, a citizen of the United States, residing at Kennett Square, in the county of Chester and State of Pennsylvania, have invented certain new and useful Improvements in Electric Regulators, of which the following is a specification.

This invention is a regulator for work systems, such for instance as the lighting system of a trolley car, and has for its object to provide new and improved means for maintaining the work circuit, in the present instance the lamp circuit, normal or substantially normal under variations of voltage in the supply circuit.

The present invention involves the use of a plurality of resistors in series with the work circuit, which resistors are successively cut in or out under successive changes in voltage, and in this connection it is an important object of the present invention to provide for dividing the effect of each resistor as well as to obtain the full effect of each resistor and thereby to effect a maximum control with a minimum number of resistors.

A further object of the invention is to provide for multiplying the controlling effect of the resistors, or in other words to permit repeated use of the resistors for compensating for further changes in voltage after each complete use of the successive resistors.

With these and other objects in view, the present invention consists in the combination and arrangement of parts, as will be hereinafter more fully described, shown in the drawings, and particularly set forth in the appended claims, it being understood that changes in the form, proportion, size and minor details may be made, within the scope of the claims, without departing from the spirit or sacrificing any of the advantages of the invention.

In the drawings,

Figure 1 is a diagrammatic view of an electric system, for instance a trolley car lighting system, embodying the regulator of the present invention.

Fig. 2 is a similar view of a modification.

Like characters of reference designate corresponding parts in all the figures of the drawings.

Referring at first more particularly to

Fig. 1 of the drawings, the reference character T designates a conductor, such for instance as a trolley wire, leading from a source of supply. The conductor 1, such for instance as a trolley pole, leads from the supply conductor T, and is in turn connected to a conductor 2, which is divided into two branches, one branch 3 being connected to one winding of an electro-magnet A, the other branch 4 being connected to another winding of the same magnet. It will be noted that the windings of this magnet are reverse to one another, the purpose of which is to neutralize the effect of the magnet on the armature 5, so that the latter is normally pulled away from the magnet by the spring 6 for a purpose as will be hereinafter explained. A conductor 7 leads from one of the windings of the magnet A to a ground or return 8, for instance a car wheel, and in this conductor or circuit is included a plurality of magnets B, C, D, E, F and G. The magnets B, C, D, E and F are in series, whereas only one winding of the magnet G is in series with said other magnets B to F, inclusive. Beyond the magnet G there are included in the circuit 7, the resistors H and I, the resistor H being very high with respect to the resistor I. The circuit or conductor 7 leads from the resistor I to the other winding of the magnet G, and thence to the ground or return 8. From the foregoing description, it will be seen that the winding A' of the magnet A, the magnets B, C, D, E and F, the winding G' of the magnet G, the resistors H and I, and then the winding G² of the magnet G, are all included in series in the circuit 7. The magnets B to G, inclusive, are provided respectively with the armatures B', C', D', D, F' and G³, and under normal conditions the several magnets are energized and the respective armatures pulled over by the magnets against the pull of the respective springs B², C², D², E², F² and G⁴.

Leading from the winding A² of the magnet A is a conductor 9 constituting a supply for the work circuit, here shown as a lamp circuit including the lamps 10. Included in the return conductor 11 of the lamp circuit is an electro-magnet J in series with the lamp circuit, and from this magnet J the conductor 11 leads through a series of resistors J³, B³, C³, D³, E³ and F³. The cir-

cuit or conductor 11 joins the circuit or conductor 7 at the point X between the resistors H and I, and from the point X the two circuits follow a common path through the 5 resistor I, the windings G² of the magnet G, and thence to the ground or return 8.

For convenience in understanding the operation of the present system, it will be noted that the supply circuit is split or divided at 10 the point Y, one branch including the conductor 3, the winding A' of the magnet A, the conductor 7, the magnets B, C, D, E and F, the winding G' of the magnet G, the resistors H and I, and the winding G² of the magnet G and that part of the conductor 7 to the ground or return 8, which circuit will hereinafter be referred to as the controlling circuit. The other branch leading from the point Y includes the conductor 4, 15 the winding A² of the magnet A, the lamp circuit, the magnet J, the conductor 11, the successive resistors J³, B³, C³, D³, E³ and F³, the resistor I, the winding G² of the magnet G and that part of the conductor 7 to the 20 ground or return 8, which circuit will hereinafter be referred to as the work circuit. It will here be noted that each of these circuits is independent of the other to the point X, and from the point X on to the 25 ground or return 8 the two circuits follow a common path. At this point it will be noted that the magnet J is in series with the work circuit or lamp circuit, while the magnets B to G, inclusive, are in series with the controlling circuit 7, so that the magnet 30 J is controlled by fluctuations in the work circuit or lamp circuit, while the magnets B to G, inclusive, are controlled by fluctuations in the controlling circuit.

35 The magnet J is provided with an armature J' and a spring J² opposing the action of the magnet. A contact J⁴ is provided for the armature J', and similar contacts B⁴ to F⁴, inclusive, are provided for the successive magnets B to F, inclusive. A corresponding contact G⁵ is provided for the magnet G. The contact J⁴ is included in or connected to the conductor 11 which leads from the magnet J to the resistor J³. A 40 conductor 12 leads from the armature J' to the conductor 11 at a point between the resistors J³ and B³, and similar conductors 13, 14, 15, 16 and 17 lead from the respective armatures B' to F', inclusive, to the conductor 11 at points between the 45 respective adjacent resistors B³ to F³, inclusive. The contacts B⁴ to F⁴, inclusive, are included in or connected to the conductors 12, 13, 14, 15 and 16. The armatures F' and 50 G⁵ are electrically connected by a conductor 18.

Under normal conditions, that part of the electric current which passes to the winding A² of the magnet A goes to the work circuit 55 or lamp circuit, thence through the winding

of the magnet J, thence through the successive resistors J³, B³, C³, D³, E³, F³ and I, to the winding G² of the magnet G, and thence to the ground or return 8, whereby the work circuit is properly supplied. On the other 70 hand, that part of the electric current which is supplied to the winding A' of the magnet A passes through the conductor 7, the successive magnets B, C, D, E and F, the winding G' of the magnet G, the resistors H and I, the winding G² of the magnet G to the return 8, whereby the controlling circuit is 75 properly supplied.

By reason of the fact that the windings A' and A² of the magnet A are reverse to one another, they of course neutralize one another. Therefore, the armature 5 is held retracted by the spring 6. Should the work circuit, which includes the lamps 10, burn out or fail, then the winding A² of the magnet A would become deenergized and consequently the winding A' would pull over the armature 5 against the contact 19 which is included in a conductor 20 leading from the conductor 2. The armature 5 is included 85 in another circuit 21 which includes lamps 22, so that any failure in the main lamp circuit 9, 10, 11, will automatically cut in the supplementary lamp circuit 21, 22.

Under normal conditions, all of the resistors are included in their respective circuits and the magnets J and B to G, inclusive, are energized and pull over their respective armatures away from the respective contacts.

Any fall in the supply through the conductor 2 does not affect the magnet A, because it produces an equal change in the windings A' and A², and consequently the armature 5 remains retracted, but a fall in 95 the supply will, of course, be felt in the work or lamp circuit, and when the fall reaches a predetermined degree, the magnet J will have become weakened to such an extent that the spring J² will overcome the pull of the 100 magnet and throw the armature J' into engagement with the contact J⁴, thereby cutting out the resistor J³ because the current will pass from the magnet J, through the conductor 11, to the contact J⁴, to the armature J', to the conductor 12, to the resistor B³, and thence on through the work circuit. Having shunted or cut out the resistor J³, the supply to the work or lamp circuit will 105 jump up in accordance with the resistance 110 cut out and consequently be restored to normal or substantially so. It will here be explained that the magnets B to G, inclusive, are actuated by different strengths of current and said magnets operate successively from 115 B to G. Such a minimum fall in current as will weaken the magnet J to the extent that its armature will be pulled over by the spring J² will not sufficiently weaken the power of the remaining magnets as to release them, 120 125 130

and consequently only the resistor J^3 will be cut out by a minimum predetermined fall of current in the supply conductor 2.

The resistors B^3 , C^3 , D^3 , E^3 and F^3 are of equal resistance, which, for convenience in explaining the operation of the invention, will be stated as 10, while the resistance of the resistor J^3 will be arbitrarily stated as 5, or in other words, substantially one-half of that of any one of the resistors B^3 to F^3 , inclusive. The resistance of the resistor I will be stated at 50, or substantially equal to the sum of the resistors B^3 to F^3 , inclusive. The resistance of the resistor H is very large as compared with that of the other resistors, say for instance, 5000. The purpose of this resistor is to prevent burning out of the magnets B to G , inclusive, said resistor H being included in series with the magnets and always in the magnet circuit.

In the operation of the system, as thus far described, normal conditions prevailing, one branch of the current which splits at the point Y passes through the magnet circuit including the magnets B to G , inclusive, the resistors H and I , the winding G^2 of the magnet G , and thence to the ground or terminal 8, the other branch of the work circuit passing around the winding A^2 of the magnet A , the lamp circuit 10, the magnet J , the conductor 11 leading thereto to the resistor J^3 , the resistors B^3 to F^3 , inclusive, to the point X where the work circuit joins the magnet circuit and follows the latter circuit through the resistor I , to the terminal or ground 8. Under these normal conditions, the windings of the magnet A are neutralized and the armature 5 is not attracted, whereas the magnets J and B to G , inclusive, are energized and pull over their armatures or switches, whereby all of the resistors are in series with the work circuit. Should the voltage of the supply circuit fall a predetermined minimum, say for instance, such as would be compensated for by the resistance of the resistor J^3 , which has heretofore been assumed as 5, the voltage of the work circuit will have been reduced to such an extent that the magnet J , which is in series with the work circuit, lets go the switch or armature J' , thereby cutting out the resistor J^3 , whereby the voltage of the work circuit will return to substantially its normal condition, notwithstanding the fall in voltage in the supply circuit. While the magnet J is weakened by the fall in voltage, this relatively slight fall in voltage does not reduce the strength of the magnets B to G , inclusive, sufficiently to let go any of their armatures or switches, and consequently all of the other resistors remain in their normal condition. Should a further fall in voltage occur in the work circuit, say for instance, a fall of 10, which is such as would be compensated for by the resistance of the resistor B^3 , then the

strength of the magnet B will be so reduced that it will let go of the switch or armature B' , thereby cutting out the resistor B^3 . By thus cutting out the resistors J^3 and B^3 , a resistance equal to 15 has been cut out of the work circuit, but as the fall in the supply circuit has been only such as would be corrected for by 10, the voltage in the work circuit will jump up 5, thereby increasing the strength of the magnet J sufficiently to pull over the switch or armature J' , and cutting in the resistor J^3 , whereby only the resistor B^3 will be cut out, which will take care of the drop of 10 in the supply circuit. A further drop of 5 in the supply circuit, making a total drop of 15, will cut out the resistor J^3 , as hereinbefore described. As the resistors J^3 and B^3 are now cut out, the drop of 15 will be properly taken care of. Should a further drop of 5 occur, making a total drop of 20, the magnet C will become weakened sufficiently to let go its switch or armature C' , thereby cutting out the resistor C^3 , so that the three resistors J^3 , B^3 and C^3 will now be cut out, making a total resistance of 25 which has been cut out, but as there has been a drop of only 20, the work circuit will jump up 5, which will increase the strength of the magnet J sufficiently to pull over the armature J' and cut in the resistor J^3 , which reduces the resistance cut out to the resistors B^3 and C^3 , which are equal to 20, and consequently take care of the drop of 20 in the work circuit.

Further successive drops in voltage are taken care of by the successive resistors D^3 , E^3 and F^3 .

When there has been such a drop in voltage as requires the cutting out of the resistors J^3 and B^3 to F^3 , inclusive, any further drop in the voltage will weaken the magnet G , which will then let go the switch or armature G^2 , which cuts out the resistor I , whose value is 50 and equal to the sum of the resistors B^3 to F^3 , inclusive. The cutting out of the resistor I takes out of the circuit a much greater resistance than is necessary to take care of the fall in voltage, and consequently the voltage of both the controlling circuit and the work circuit will jump up, resulting in such a strengthening of the magnets J and B to F , inclusive, as to pull over their respective armatures or switches, thus cutting into the work circuit the resistors J^3 and B^3 to F^3 , inclusive. Any further drop in the voltage of the supply circuit will be taken care of, first, by cutting out the resistor J^3 , then by cutting out the resistor B^3 , and so on throughout the series of resistors, as hereinbefore described.

When the winding G^2 of the magnet G , as well as the resistor I , has been cut out, as hereinbefore described, only winding G' of the magnet G is thereafter energized, and

as the winding G' is such that the strength of the magnet is not enough to overcome the spring G^4 , the leg G^2 and the resistor I will remain cut out under a predetermined low voltage in the supply circuit, and consequently the successive resistors J^3 and B^3 to F^3 will be controlled by the magnets J and B to F , inclusive, as hereinbefore described, without interference by the magnet G .

After a fall in voltage has taken place and then the voltage tends to rise toward normal, the action of the apparatus is exactly reverse to that just described. When the voltage tends to rise toward normal, the magnets F to B cut in their respective resistors. When their total resistance is no longer sufficient to correct for the rise in voltage, the magnet G attracts the armature G^3 and cuts in the resistor I , thus introducing a much greater resistance than is necessary to take care of the rise in voltage. This operation of magnet G is due to the fact that windings G^1 and G^2 are so proportioned to each other than when the armature is released and cuts out the resistor I and the winding G^2 , the resultant increase of current in the winding G^1 all but compensates for the cutting out of the winding G^2 . In fact it has been found desirable to so proportion windings G^1 and G^2 that when the current falls ever so slightly below an arbitrary strength that armature G^3 is released and when it rises again ever so slightly above the same point, that armature G^3 is again attracted.

From the foregoing description, it will be understood that after the resistors B^3 to F^3 , inclusive, have been employed to take care of changes in voltage, they may again be employed for the same purpose by cutting out the resistor I , so that a wide range of control may be effected by a relatively few resistors. While five resistors B^3 to F^3 , inclusive, have been shown, it is quite apparent that a greater or less number of resistors may be employed, depending entirely upon the conditions to be taken care of.

In the arrangement shown in Fig. 1 of the drawing, the resistors B^3 to F^3 , inclusive, may be twice employed, but further repeated uses of said resistors may be obtained in the manner illustrated in Fig. 2 of the drawing, which differs from Fig. 1 of the drawing, merely in the addition of two resistor sections and their respective controlling magnets or devices corresponding precisely to the resistor I and its magnet or controlling device G . According to this arrangement, where the conductor 7 leaves the winding G' , instead of passing directly to the resistor H , it passes to the winding K' of a magnet K similar to the magnet G ; thence to the winding L' of the magnet L , similar to the magnet G , and then to the resistor H .

From the winding G^2 of the magnet G , a conductor 23 leads to a resistor K^6 , corresponding to the resistor I . From the resistor K^6 , a conductor 24 leads to the winding K^2 of the magnet K , and from this winding a conductor 25 leads to a resistor L^6 , corresponding to the resistor I , and this resistor L^6 is connected with the winding L^2 of the magnet L , from which the conductor 7 connects with the ground or return 8. From the conductor 23, a branch 23^a extends to the armature K^3 of the magnet K . A spring K^4 is provided for the armature K^3 , and for the latter there is provided a contact K^5 included in the conductor 25. From the conductor 25 a branch 25^a leads to the armature L^3 , which is provided with a spring L^4 . A contact L^5 is provided for the armature L^3 , and from this contact L^5 the conductor 7 leads to the ground or terminal 8. While only two additional resistors have been shown in Fig. 2, it is quite apparent that any number of resistors may be employed without requiring any changes whatsoever in the invention.

The operation of the arrangement shown in Fig. 2 is precisely the same as described for Fig. 1, inasmuch as the resistors B^3 to F^3 will be successively cut out, after which a further fall in voltage will result in the cutting out of the resistor I and the returning of the resistors B^3 to F^3 , inclusive, to the work circuit. After a second cutting out of the resistors B^3 to F^3 , inclusive, a further fall in voltage will result in the cutting out of the resistor K^6 , which resistor will have the arbitrary value of about 100 so as to equal the sum of the resistors B^3 to F^3 , inclusive, and the resistor I , whereby said resistors B^3 to F^3 , inclusive, and I , will be restored to the work circuit, and repeated use thereof may be obtained. A similar operation occurs when the fall of voltage is such as to cut out the resistor L^6 , which will have the arbitrary value of 200.

While I have described the invention as taking care of falls in voltage from some predetermined high voltage, it is quite apparent that the same apparatus may be employed for taking care of rises in voltage from some predetermined standard of voltage, merely by having all of the armatures or switches normally held over against their respective contacts, thereby maintaining all of the resistors, with the exception of the resistor H , cut out of the circuit. Under these conditions, rises in voltage will successively strengthen the magnets, and thereby successively pull the armatures or switches away from their contacts, and thus cut into the circuit the respective resistors. In other words, if the device is to take care of falls in voltage, the relays or magnets are arranged to normally attract the armatures or switches, while to take care of rises in

voltage the magnets or relays are arranged to have the armatures or switches pulled over against their respective contacts by the respective springs, and no further change 5 whatsoever is necessary in the apparatus. It will therefore be understood that the same apparatus is capable of taking care of falls in voltage by adjusting the relays as described, and also may be employed to take 10 care of rises in voltage by another adjustment of the relays.

Having thus described the invention, what is claimed is:—

1. In an electric system, the combination 15 of a supply circuit, a work circuit, a plurality of resistors in series with the work circuit, means for cutting in and out the respective resistors by changes in the voltage of the supply circuit, a relatively weak resistor in the work circuit, and means responsive to work circuit conditions for cutting into or out of the work circuit said relatively weak resistor.
2. In an electric system, the combination 25 of a supply circuit, a work circuit, a plurality of resistors in series with the work circuit, means for cutting in and out the respective resistors by changes in the voltage of the supply circuit, an additional resistor 30 in the work circuit, and means for cutting in and out said last named resistor by changes of current in the work circuit.
3. In an electric system, the combination 35 of a supply circuit, a work circuit, a plurality of resistors in series with the work circuit, means for cutting in and out the respective resistors by changes in the voltage of the supply circuit, and means responsive to work circuit conditions for altering 40 the resistance of the work circuit.
4. In an electric system, the combination 45 of a supply circuit, a work circuit, a plurality of resistors in series with the work circuit, means for cutting in and out the respective resistors by changes in the voltage of the supply circuit, an additional resistor in the work circuit, and means actuated by 50 the work circuit for cutting into or out of the work circuit said additional resistor.
5. In an electric system, the combination 55 of a supply circuit, a work circuit, a plurality of resistors in series with the work circuit, means for cutting in and out the respective resistors by changes in the voltage of the supply circuit, an additional resistor in the work circuit and means included in series with the work circuit for cutting into or out of the work circuit said 60 additional resistor.
6. In an electric system, the combination 65 of a supply circuit, a work circuit, a plurality of main resistors in series with the work circuit, a relatively weak resistor also in series with the work circuit, a shunt circuit for each resistor, means in the supply

circuit and responsive to supply circuit conditions for controlling the shunt circuits of the main resistors, and means in the work circuit and responsive to work circuit conditions for controlling the shunt circuit of 70 the relatively weak resistor.

7. In an electric system, the combination of a supply circuit, a work circuit, a series of main resistors in the work circuit, a relatively weak resistor also in the work circuit, 75 a shunt circuit for each resistor, a switch for each shunt circuit, a series of magnets for the switches of the respective main resistors, said magnets being included in the supply circuit and responsive to changes in the supply circuit and a magnet for the switch of the shunt circuit of the relatively weak resistor.

8. In an electric system, the combination 85 of a supply circuit, a work circuit, a series of main resistors in the work circuit, a relatively weak resistor also in the work circuit, a shunt circuit for each resistor, a switch for each shunt circuit, a series of magnets for the switches of the respective main resistors, said magnets being included in the supply circuit, and responsive to changes in the supply circuit, and a magnet for the switch of the shunt circuit of the relatively 90 weak resistor, the strength of the magnets 95 increasing from the magnet of the relatively weak resistor progressively throughout the series of magnets for the main resistors.

9. In an electric system, the combination 100 of a supply circuit, a work circuit, a plurality of resistors in series with the work circuit, means for successively cutting in or out the respective resistors by successive changes in the voltage of the supply circuit, and means actuated by further change of voltage 105 when all of the resistors have been cut in or out to restore said resistors to their former condition and to permit repeated successive cutting in or out thereof by further change in voltage in the supply circuit. 110

10. In an electric system, the combination 115 of a supply circuit, a work circuit, a plurality of resistors in series with the work circuit, means for successively cutting in or out the respective resistors by successive changes in the voltage of the supply circuit, means actuated by further change of voltage when all the resistors have been cut in or out to restore said resistors to their former condition and to permit repeated successive cutting in or out thereof by further change in voltage in the supply circuit, and means responsive to work circuit conditions for reducing any excessive effect of cutting in or 120 out any resistor.

11. In an electric system, the combination 125 of a supply circuit, a work circuit, a plurality of resistors in series with the work circuit, means for successively cutting in or out the respective resistors by successive

changes in the voltage of the supply circuit, a supplemental resistor in series with the work circuit and approximately equal to the sum of the series of resistors, and means 5 to cut in or out the supplemental resistor under a further change in voltage when the series of resistors has been cut in or out, thereby to restore the series of resistors to their previous condition and permit successive 10 cutting in or out thereof under further changes in voltage.

12. In an electric system, the combination of a supply circuit, a work circuit, a plurality of resistors in series with the work circuit, 15 means for successively cutting in or out the respective resistors by successive changes in the voltage of the supply circuit, a supplemental resistor in series with the work circuit and substantially equal to the sum of 20 the series of resistors, a shunt circuit for the supplemental resistor, a switch for the shunt circuit, a magnet for the switch to permit cutting in or out of the supplemental resistor by a further change in voltage when 25 the series of resistors have been cut in or out.

13. In an electric system, the combination of a supply circuit, a work circuit, a plurality of resistors in series with the work circuit, means for successively cutting in or 20 out the respective resistors by successive changes in the voltage of the supply circuit, a supplemental resistor in series with the work circuit and substantially equal to the sum of the series of resistors, a shunt circuit 35 for said supplemental resistor including a switch, and a magnet having two windings for the switch, one winding of the magnet being in shunt with the supply circuit, and one winding of the magnet being in series 40 with the work circuit, said magnet being responsive to further changes in voltage to cut in or out the supplemental resistor when the series of resistors has been cut in or out.

14. In an electric system, the combination of a supply circuit, a work circuit, a plurality of resistors in series with the work circuit, means for successively cutting in or out the respective resistors by successive changes in the voltage of the supply circuit, 45 a first supplemental resistor in series with the work circuit and substantially equal to the sum of the series of resistors, means to cut in or out the first supplemental resistor under a further change in voltage when the 50 series of resistors has been cut in or out, thereby to restore the series of resistors to their previous condition and permit further successive cutting in or out thereof under further changes in voltage, a second supplemental resistor in series with the work circuit and substantially equal to the sum of 55 the series of resistors plus the first supplemental resistor, and means to cut in or out the second supplemental resistor under a still further change of voltage when the 60

series of resistors plus the first supplemental resistor has been cut in or out, thereby to restore the series of resistors plus the first supplemental resistor to their previous condition and permit successive cutting in or out thereof under further changes of voltage. 70

15. In a system of voltage regulation, the combination with a supply circuit and a translating circuit, of a plurality of resistors in series with the translating circuit, a 75 coil responsive to variations in current in said translating circuit for controlling at least one of said resistors, a plurality of successively acting coils responsive to the voltage of said supply circuit for controlling 80 others of said resistors.

16. In a system of voltage regulation, the combination with a supply circuit and a translating circuit, of a plurality of resistors in series with the translating circuit, 85 some of the resistors being of substantially the same resistance, and one of the resistors being of a less resistance, a coil responsive to variations in current in said translating circuit for controlling the resistor of less resistance, and a plurality of successively acting coils responsive to the voltage of said supply circuit for controlling the other resistors. 90

17. In a system of voltage regulation, the combination with a supply circuit and a translating circuit, of a plurality of resistors in series with the translating circuit, a coil responsive to variations in current in said translating circuit for controlling at 95 least one of said resistors, a plurality of successively acting coils responsive to the voltage of said supply circuit for controlling others of said resistors, and means actuated by further change of voltage when all of the resistors have been cut in or out to restore said resistors to their former condition and to permit repeated successive cutting in or out by further change in voltage in the supply circuit. 100

18. In a system of voltage regulation, the combination with a supply circuit and a translating circuit, of a plurality of resistors in series with the translating circuit, a coil responsive to variations in current in 115 said translating circuit for controlling at least one of said resistors, a plurality of successively acting coils responsive to the voltage of said supply circuit for controlling others of said resistors, and means actuated by further change of voltage when all of the resistors have been cut in or out to repeatedly 120 restore said resistors to their former condition and to permit repeated successive cutting in or out thereof by further change in 125 voltage in the supply circuit.

19. In an electric system, the combination of a supply circuit, a work circuit, compensating means responsive to changes in voltage in the supply circuit, and additional 130

- means responsive to further changes in voltage in the supply circuit when the compensating means has reached its maximum to restore the compensating means for its former condition to permit repeated action of the compensating means by further change in voltage in the supply circuit.
20. In an electric system, the combination of a supply circuit, a work circuit, compensating means responsive to changes in voltage in the supply circuit, and additional means responsive to circuit conditions in one or both of the circuits when the compensating means has reached its maximum to restore the compensating means to its former condition to permit repeated action of the compensating means by further change in voltage in the supply circuit.
21. In an electric system, the combination of a supply circuit, a work circuit, regulating means for the work circuit, said regulating means being responsive to the electric conditions in one of said circuits, and additional means responsive to electric conditions in the work circuit for extending the range of the regulating means.
22. In an electric system, the combination of a supply circuit, a work circuit, regulating means for the work circuit, said regulating means being responsive to the electric
- 30

conditions in one of said circuits, and additional means responsive to electric conditions in one or both of the circuits for extending the range of the regulating means.

23. In an electric system, the combination of a supply circuit, a work circuit, regulating means for the work circuit, said regulating means being responsive to the electric conditions in one of said circuits and capable of coarse regulation, and additional means responsive to electric conditions in the work circuit and co-operating with said regulating means to secure finer regulation than can be secured by the first mentioned regulating means alone.

40

24. In an electric system, the combination of a supply circuit, a work circuit, a plurality of regulating means for the work circuit and controlled by the supply circuit, and additional means responsive to work circuit conditions for regulating the work circuit alternately with each regulation of the plurality of regulating means.
